Des. 221,249
Registered July 20, 1971

221,249

ELECTRIC IRON

Eugene R. Russell, Boonville, Mo., assignor to McGraw-
Edison Company, Milwaukee, Wis.
Filed Apr. 2, 1970, Ser. No. 22,211

Term of patent 14 years

Int. Cl. D7—06

U.S. Cl. D49—6

Fig. 4

Fig. 5

Fig. 6

FIG. 1 is a top plan view of the subject iron;
 FIG. 2 is a side elevational view of the subject iron;
 FIG. 3 is a bottom plan view of the subject iron;
 FIG. 4 is a front elevational view;
 FIG. 5 is a rear elevational view of the subject iron;
 FIG. 6 is an outline view of the iron as seen generally from line 6—6 in FIG. 1.

I claim:
 The ornamental design for an electric iron, substantially as shown.
